Primary Examiner — Lakiya G Rogers*Assistant Examiner* — Harold E Blackwell, II(74) *Attorney, Agent, or Firm* — Jeffrey A. Proehl;
Woods, Fuller, Shultz & Smith, PC(57) **CLAIM**

The ornamental design for a trailer door holding device, as shown and described.

DESCRIPTION

FIG. 1 is a perspective view of the trailer door holding device of the present disclosure;

FIG. 2 is a front elevational view of the trailer door holding device;

FIG. 3 is a right side elevational view of the trailer door holding device;

FIG. 4 is a rear elevational view of the trailer door holding device;

FIG. 5 is a left elevational view of the trailer door holding device;

FIG. 6 is a bottom plan view of the trailer door holding device; and,

FIG. 7 is a top plan view of the trailer door holding device.

1 Claim, 3 Drawing Sheets(56)
